ABRASIVE WHEEL

Robert R. Raber, West Hartford, Conn., assignor,
by mesne assignments, to Niles-Bement-Pond
Company, New York, N. Y., a corporation of
New Jersey

Application November 30, 1934, Serial No. 755,293.

4 Claims. (Cl. 51—209)

This invention relates to abrasive wheel mountings and particularly to a wheel head for surface grinding machines adapted to have detachably mounted therein a plurality of abrasive blocks or segments arcuate in form and arranged in a circle concentric to the axis of rotation of the head.

This application describes and claims an improvement upon the Abrasive wheel disclosed in Hoagland Patent No. 1,797,526 granted March 24, 1931.

An object of the present invention is to provide a strong, rigid head adapted to mount a plurality of separated arcuate or segmental abrasive blocks within a single circle, the construction forming substantially a homogeneous unitary structure built up of steel members autogenously welded to each other for operation at high rotative speeds.

Another object of the invention is to provide a wheel head having a solid ring of rolled or forged steel sufficiently heavy to withstand the stresses of severe operation of the wheel head at high rotative speeds.

Another object of the invention is to provide improved means for positioning the abrasive blocks forwardly after they have become worn, abutment members for this purpose being rotatable into and out of positions to engage the inner or upper end surface of the abrasive blocks.

With the above and other objects in view, my invention consists in the features of construction and operation set forth in the following specification and illustrated in the accompanying drawings.

In the accompanying drawings annexed here-to and forming a part of this specification, I have shown my invention embodied in a wheel head for relatively large diameters and adapted for application to a vertical surface grinding machine, but it will be understood that the invention can be otherwise embodied and that the drawings are not to be construed as defining or limiting the scope of the invention, the claims appended to this specification being relied upon for that purpose.

In the drawings:

Figure 1 is a vertical sectional view taken centrally through the axis of rotation of the wheel head on the broken line 1—1 of Fig. 2.

Fig. 2 is a partial plan view of the wheel head looking at the under side of the head as seen in Fig. 1.

Fig. 3 is an isometric view of the under side of the wheel head showing several abrasive segments in operative position and also indicating the posi-

tion of an abutment member adjusted for a worn abrasive segment.

Fig. 4 is a vertical sectional view taken through a space between adjacent abrasive blocks showing the abutment member in position for short blocks.

Fig. 5 is an isometric view looking toward the rim of a portion of the wheel head showing the abutment member in position for short blocks similar to that shown in Fig. 4, and

Fig. 6 is a sectional view taken diametrically through a portion of the wheel head prior to machining operations thereon showing the assembly of members composing the wheel head and the means for rigidly securing them together.

In the above mentioned drawings I have shown but one embodiment of the invention which is now deemed preferable, but it is to be understood that changes and modifications may be made within the scope of the appended claims without departing from the spirit of the invention.

Briefly, and in its broadest aspect, my invention may include the following principal parts: First, an annular or cylindrical ring; second, a top plate suitably formed on or secured to the ring member; third, abrasive segmental blocks clamped in spaced positions to the inner surface of the ring member; fourth, reinforcing ribs formed within the supporting ring and engaging one end of each abrasive block or segment; fifth, rotatable abutment members cut away on one side and rotatable into and out of positions bearing against the inner or upper end surface of the abrasive blocks; and sixth, strap clamps engaging contiguous portions of adjacent abrasive blocks and bolted or otherwise secured to the annular supporting ring.

Referring more in detail to the figures of the drawings and first referring to Figs. 1, 2 and 3, it will be seen that the head or wheel mounting includes a ring member 10 the inner cylindrical surface of which forms a rigid bearing surface for the abrasive segmental blocks 11. The top plate 12 forming part of the head and formed integrally with or rigidly secured to the ring 10 is provided with means whereby the head or mounting may be attached to the spindle 13 of a grinding machine. These means may include a plurality of screws 14 but one of which is shown passing through a flange 15 formed on the spindle 13 and entering threaded holes within a recessed portion 50 of the top plate 12 carefully surfaced and adapted to contact with the flange 15 on the spindle 13.

In order to form abutments for the abrasive blocks when initially placed in the head and when

they are of full length, studs 16 may be inserted suitably spaced apart in the top plate 12 so that there will be two of these studs 16 engaging each of the abrasive segments 11 preferably adjacent to the opposite end surfaces thereof.

In order to secure the abrasive blocks or segments 11 in fixed position within the head, clamping straps 17 are provided securely clamping the abrasive segments against the inner surface of the ring 10 by being connected directly thereto by elongated screws 18 shown in Figs. 2 and 3. Each strap 17 bears against the closely spaced ends of adjacent blocks 11 and may preferably have angularly adjustable bearing members 19 inserted therein to accommodate themselves to the blocks. Spaced along the inner surface of the ring member 10 are inwardly extending reinforcing ribs 20 against which an end surface of each abrasive segment may engage and through which may extend the screws for clamping the abrasive blocks in position. These ribs 20 therefore form lateral abutments for the blocks 11.

In order to form rigid stops or abutments for the abrasive segments after they have become worn and have been set out in order to expose another portion thereof, circular abutment members 22 are provided within the ring member and secured rotatably to the top plate member 12 as by means of screws 23 shown in Figs. 1 and 2. It will be seen from an inspection of Fig. 2 that these rotatable abutment members 22 may be adjusted about their supporting screws 23 to operative or inoperative position. Each of these abutment members 22 also is cut away along one side 35 closely parallel to a diameter. In the position shown in Fig. 2 the rotatable abutment members 22 are out of contact with the abrasive blocks 11 and are simply retained in inner or inoperative position against the top plate 12. When the abrasive blocks or segments 11 have been unclamped and moved outwardly after having been worn the abutment members 22 are rotated substantially 180° which bring the periphery of these members directly under adjacent portions of contiguous blocks 11. In this adjusted position the members 40 form supporting surfaces for the blocks 11 materially spaced outwardly from the bearing surface provided by the studs 16 in the top plate member 12. The clamping straps 17 may be used 45 without any change in their position with the abrasive blocks 11 and the rotatable abutment members 22 in either position. In their operative position the members 22 engage adjacent ends of adjacent blocks 11 so that each block 11 is supported by two of the members 22. As shown in Figs. 2 and 5, the members 22 may be centrally 50 recessed to provide a relatively narrow bearing surface about its periphery on one side.

Referring now to Fig. 6, it will be seen that the entire body portion of the head is made up of steel members of simple form which may be obtained in rolled or forged shapes. These pieces are shown in section in Fig. 6 prior to any machining operations thereon but after they have been welded in position. It will be seen that the ring member 10 and the top plate member 12 are

secured together by means of a weld extending completely around the body of the mounting at the upper edge of the ring member and at the outer periphery of the top plate. The means for securing the head detachably to the spindle includes a second plate or ring member 12^a welded as shown to the inner periphery of the plate member 12 and at the upper portion of the outer periphery of the added plate. Inserted within the ring member 10 and bearing against the plate member 12 are web members 25 reinforcing the structure and also the abutment members 20 welded to the lower portion of the webs and to the lower edge of the ring member at spaced points about the periphery of the head. With the members autogenously welded into position, which may readily be done by arc or oxy-acetylene welding and suitably annealing the members thereafter, the head is machined to the desired dimensions and form indicated in Figs. 1 and 2.

What I claim is:

1. An abrasive wheel head comprising in combination, a body member, reinforcing members therein, abrasive blocks within said body member positioned against said reinforcing members, clamping means for said blocks, and rotatable plate-like members pivotally supported upon fixed axes within said body member adapted in one position to engage the inner ends of adjacent blocks to support said blocks in advanced positions.

2. An abrasive wheel head comprising in combination, a body member, reinforcing members therein, abrasive blocks within said body member positioned against said reinforcing members, clamping means for said blocks, and rotatable plate-like members pivotally supported upon fixed axes within said body member movable to positions into and out of engagement with the inner ends of the abrasive blocks whereby said blocks may be supported in two positions within said head.

3. An abrasive wheel head comprising in combination, a body member, abrasive blocks therein, clamping means for said blocks engaging adjacent ends of contiguous blocks, and rotatable plate-like members pivotally supported upon fixed axes within said body member disposed adjacent the inner ends of said blocks and rotatable to positions into and out of engagement with the inner end surfaces of said blocks, each rotatable member in its block supporting position engaging adjacent ends of contiguous blocks.

4. An abrasive wheel head comprising in combination, a body member, abrasive blocks disposed within a circle, clamping means for said blocks, and rotatable plate-like members pivotally supported upon fixed axes arranged within a circle within the body member, said rotatable members being disposed adjacent the inner ends of said blocks and rotatable to positions engaging the inner ends of said abrasive blocks whereby said blocks may be supported in advanced positions by said rotatable members.
